BRACELET OR THE LIKE

Michael Chernow, Brooklyn, N. Y.

Application October 29, 1935, Serial No. 47,214

5 Claims. (Cl. 63—4)

My present invention relates to jewelry of the chain or strand type, including bracelets, necklaces, anklets, tie guards, tiaras and the like.

The invention provides an article of the above type to be selectively made up as required in a retail shop from elements kept in stock, to include one or more desired emblems or symbols making up, in the most specific application, the initials or the Christian name of the wearer.

10 It is a specific object to provide stock elements of low cost, devoid of delicate attachment conformations which can with facility be selectively put together by the salesgirl and without the need for tools or adhesives of any character whatsoever, to afford a neat assemblage that is secure, yet quite limber for its intended purpose and which has the appearance of having been specially fabricated with the initials or other individual insignia of the wearer.

20 In the accompanying drawing, in which is shown one of various possible embodiments of the several features of the invention,

Fig. 1 is a plan view of a bracelet incorporating the invention,

25 Fig. 2 is a sectional view on an enlarged scale taken on line 2—2 of Fig. 1, and

Fig. 3 is a perspective view on a still larger scale of the rear of one of the initial links.

Referring now to the drawing, in which a 30 bracelet embodiment is illustratively shown, the unit may comprise a pair of terminal chain elements 10 and 11 made up of conventional small links or the like, with one or more intervening special larger links connected in sequence therebetween. The respective outer ends of the terminal chain elements have conventional coacting clasp elements 10' and 11'.

Links L are illustratively shown in the drawing in the form of letters or initials, illustratively 40 "REF". Each of these links is made up of a relatively rigid block, ordinarily of malleable metal such as gold or silver, or in the cheaper embodiment of plated brass. The characters are of an ornamental type, preferably with rectilinear parallel lateral edges 12 and 13, and preferably of 45 that type of ornamental design which affords a continuous lateral edge for at least one half the height of the character as shown.

Unitary with each of the initials or characters are complementary fastening appurtenances for connecting the same in sequence and in hinged relation. For this purpose there is preferably provided at the middle of one lateral edge, illustratively the left edge 12, a unitary eye 14, 55 which is preferably flush with the rear face of

the metal block and is of thickness much less than that of the block.

At the middle of the right edge 13, the root 15 of a narrow tongue protrudes flush with the rear face of the block and said tongue is curved over 5 into a looped hook 16 with its free end 17 adjacent its anchored end. The process of stamping the malleable metal of the block near its ends to form the thin eye 14 and hook 16, results in compacting and thus hardening the metal of the hook and eye, thereby rendering the same resilient. Thus, it is seen, that in assembling the bracelet or other article, the hook 16 will spread open slightly as it is passed into the eye 14 of the contiguous link. The hook will resiliently return to initial position and will thus resiliently maintain the elements against coming apart, as best shown in Fig. 2, without however impairing the free hinging movement of successive links. When it is desirable to make the links of metal 20 lacking resilience, the hook 16 could be manually pressed to locking position after it has been passed through the eye 14 of the neighboring part.

Similarly the terminal hook 18 of the final link 25 L' will snap into the eye 19 of the terminal chain element 11 at the right. The left terminal chain 10 is provided with a special hooked link 20 which coacts in the same relation with the eye 21 at the left of the first link L'. 30

In use it will be seen that the various character links will conform to the wearer and by virtue of the hinged relation of said links, the hooks 17 will be prevented from pressing against the wrist.

The retail purchaser will ask for or select the 35 desired sequence to make up the initials or the entire name, and the salesgirl simply interlinks them as above set forth.

The parts can as readily be disassembled and replaced by other links selectively to make up 40 bracelets for various occasions as desired.

The invention, while shown applied to a bracelet is of course applicable to necklaces, anklets, tie guards, tiaras, watch chains and in numerous other possible relations. 45

It will thus be seen that there is herein described an article in which the several features of this invention are embodied, and which article in its action attains the various objects of the invention and is well suited to meet the requirements of 50 practical use.

As many changes could be made in the above construction, and many apparently widely different embodiments of this invention could be made without departing from the scope thereof, it is 55

intended that all matter contained in the above description or shown in the accompanying drawing shall be interpreted as illustrative and not in a limiting sense.

5 Having thus described my invention, what I claim as new and desire to secure by Letters Patent, is:

1. An article of jewelry comprising terminal flexible strand members with coacting terminal 10 clasp elements and a plurality of intervening links, hingedly and removably connected in sequence by hook and eye connections, each of said links having a unitary hook element at the middle of one lateral edge thereof and a complementary eye element at the middle of the opposite lateral edge thereof the hook element of each link being snapped into the contiguous eye element of the neighboring link.

2. An initial bracelet comprising a pair of chain 20 elements with coacting terminal clasp elements and a succession of links removably attached in sequence between and to said chain elements, each of said links representing a letter of the alphabet with substantially rectilinear lateral edges, each 25 of said links having an integral hook element at the middle of one lateral edge thereof, and an integral eye element at the middle of the opposite edge thereof, each hook element affording resilient latch connection to the eye element of the 30 contiguous link.

3. The combination set forth in claim 2 in which each link is of relatively soft metal stock and the integral hook is compressed from said metal stock for hardening and resiliency thereof for spring latching with respect to the eye of the 5 contiguous link.

4. A link element for selective connection in a bracelet, necklace, anklet, tie guard, watch chain or the like, comprising a unitary relatively thick metal block of malleable metal, one of said links 10 having unitary therewith at the middle of one lateral edge thereof an eye construction, and having unitary therewith at the opposite lateral edge thereof a hook, said hook being compressed from the stock of said metal and thereby rendered 15 harder and more resilient for latching with respect to the eye of a contiguous link member.

5. A link element for selective connection in a bracelet, necklace, anklet, tie guard, watch chain or the like, said link comprising an ornamental 20 rigid block of malleable metal having attachment members unitary with the middles of the lateral edges thereof, comprising a hook at one side and an eye at the other side, each of said attaching members being compressed from the metal of the 25 block and being flush at the rear face thereof with the rear face of the block and of thickness much less than the thickness of the block.

MICHAEL CHERNOW. 30
